Atty.

UNITED STATES PATENT OFFICE.

BERNARD P. DARLING, OF SHORTSVILLE, NEW YORK, ASSIGNOR OF
ONE-HALF TO JOHN H. PETTIT, OF SAME PLACE.

HOISTING-MACHINE.

SPECIFICATION forming part of Letters Patent No. 336,630, dated February 23, 1886.

Application filed October 21, 1885. Serial No. 180,501. (No model.)

To all whom it may concern:

Be it known that I, BERNARD P. DARLING, of Shortsville, in the county of Ontario and State of New York, have invented a certain 5 new and useful Improvement in Hoisting-Machines; and I do hereby declare that the following is a full, clear, and exact description of the same, reference being had to the drawings accompanying this application.

10 My improvement relates to that class of hoisting-machines in which the hoisting-rope is connected with a car or carriage that runs on a track, so that when the load has been raised vertically to the car it trips the fastening of the same, and the car, with the elevated 15 load, is then drawn along to the point where the load is to be deposited. It is particularly adapted to unloading hay.

The improvement is as follows:

20 In the drawings, Figure 1 is a side elevation of the apparatus mounted on a track in the peak of a barn. Fig. 2 is an enlarged sectional elevation of the car. Fig. 3 is a plan view of the yoke or traveler that runs on the track. Fig. 25 4 is an end elevation of Fig. 1, looking in the direction of the arrow at the left. Fig. 5 is a diagram showing a rear elevation of the swinging clamp-arm and the hook for holding it elevated while the load is being drawn up 30 before the car is started. Fig. 6 is an elevation of the tripping-latch that holds the car in line with the yoke.

A shows the track on which the car runs. It may be made of wood or metal, and in the 35 case of hay-hoisting machines it is mounted in the peak of the barn.

B is the yoke or traveler, being provided with traction-rollers *a a*, that run on the track.

C is the car or carriage, the same being attached to the yoke or traveler by a swivel-bolt, *b*, which allows the car to be shifted end for end, so as to run in either direction, as will be more fully described.

D is a pulley that turns loosely in the car.

45 E is the hoisting rope or cable, which passes up over the pulley D, thence horizontally over a stationary pulley, F, over the point where the load is to be dropped, and thence down to the ground, where a horse or other power is 50 attached to it.

G is the fixed bed in the frame of the car, over which the rope passes.

H is a swinging arm, pivoted at *c*, and provided at its front end with a rack, *d*, which, when the arm is depressed, engages with a 55 pinion, *f*, made fast to the side of the pulley D. When the arm is raised, as shown in Fig. 2, the pulley runs free. The arm is provided with an enlargement, *g*, forming a clamp, resting over the bed G. The arm is also provided with a pin, *h*, which projects out through a slot, *i*, in the side of the frame of the car. When the car is at rest over the load for the purpose of raising the same, the pin *h* catches into a hook, *k*, suspended from the track 60 above, and the arm H is held elevated free from pinion *f*. When the car starts forward to convey the load, the pin *h* disengages from the hook *k* and the arm drops, bringing the rack 65 *d* into engagement with the pinion *f*. The 70 weight of the load drawing upon the rope passing over the pulley causes the latter to draw harder and harder on the arm H and clamp the rope more and more firmly between the two clamps *g G*. By this means, when the 75 load is once drawn up to the car and the car has started forward on the track, the rope is clamped and held firmly, suspending the load while the car is drawn along on the track to the point of deposit. The heavier the load 80 the more firmly will the rope be clamped. This clamping action is such as to produce no abrasion on the rope, but simply to hold it by a solid grip. The rope is entirely free while the load is being raised, the pinion and rack 85 being then disengaged and the pulley running loose. The hook *k* may be provided with a spring connecting it with the track in such a way that the tendency of the spring is to force the hook down into the vertical position and 90 prevent it from swinging or vibrating.

L L are two latches, pivoted to the yoke B and standing in opposite directions. These latches engage with stops *m m* on the track when the car is brought into the position for 95 raising the load, thus holding the car in a stationary position.

M is a slide in one end of the car C, which moves freely up and down. At the lower end is a ring, *n*, through which the rope E passes, 100

and at the upper end is a stud or pin, *o*, which passes through a hole in the top plate of the car and rests under the head of the latch *L* that stands on that side. It also has side lugs 5 or pins, *p p*, forming guides resting in slots in the side of the car. In elevating the load it rises free till it strikes the ring *n*, when it elevates the slide *M*, forcing the pin out against the end of the latch *L* and disengaging the 10 opposite end from the stop *m*, thereby freeing the car, so that it can run on the track, as before described. When the car is turned around end for end, to run the other way, the same slide answers the purpose, but the other 15 latch *L* then operates with it.

N is a catch for locking the car to the yoke or traveler. It consists of a spring attached to the under side of the top plate of the car, and provided at its outer end with a loop or 20 clevis, *r*, through which the rope passes. It also has at its top a stud, *s*, which passes up through a socket in the top plate and enters a notch in the under side of the yoke, thereby holding the car in line with yoke. The 25 sides of the yoke are made slightly inclined or beveling, to allow it to slide over the catch to engage therewith. To shift the car to run in the opposite direction, the procedure is as follows: The team is disengaged, and the rope 30 is drawn from pulley *F*, and the two ends are brought down so that they hang parallel. Then, by drawing on one end and holding the other, the spring-catch *N* will be drawn down sufficiently to disengage the catch from the 35 yoke, and then by turning or twisting the ends of the rope the car can be turned to the other position, when the catch re-engages on the opposite side. The car can then be run the other way on the track in the same manner, the rope 40 having previously been carried over a pulley, *F*, on that side. All this work of shifting the car is done below and without mounting a ladder or taking other steps than those described.

In practice, after the load has been elevated and then drawn to the point of deposit, 45 the load is released and dumped by a trip-cord, and, the strain being removed, the car, with rope attached, is drawn back to the point of starting, when the swinging arm is again

elevated by catching the hook, leaving the 50 rope free to be drawn down and attached to a new load.

Having described my invention, what I claim as new, and desire to secure by Letters Patent, is—

55

1. In a hoisting-machine, the combination of the yoke or traveler *B*, provided with friction-wheels that run on the track or way, the car or carriage *C*, swiveled by a bolt or pivot to the yoke, so that it can be turned and 60 changed end for end, and the spring-loop *N*, attached to the upper plate of the carriage, and provided with a stud, *s*, which strikes into a socket of the yoke to lock the parts together, the whole so arranged, as described, that the 65 stud can be disconnected and the carriage turned end for end on the yoke by bringing the two ends of the rope to the ground, as set forth.

2. In a hoisting-machine, the combination, 70 with the car, of a pulley turning loosely thereon, over which the hoisting-rope passes, a pinion secured to the pulley, a swinging arm provided with a rack that engages with the pinion when the arm is depressed, clamps on 75 the car and the arm, between which the rope passes, and a device for catching and holding the arm in an elevated position while raising the load, as herein set forth.

3. In a hoisting-machine, the combination, 80 with the yoke and car, of latches pivoted to the yoke, standing in opposite directions and engaging with stops on the track to hold the car stationary over the load, and a slide in the car, provided at the bottom with a ring 85 against which the load strikes, when elevated, to operate the slide, and at its top with a pin that rests under the latch on the yoke, as and for the purpose specified.

In witness whereof I have hereunto signed 90 my name in the presence of two subscr.bing witnesses.

B. P. DARLING.
